UNITED STATES PATENT OFFICE.

JOSEPH L. WILSON, OF WALTHAM, MASSACHUSETTS.

BICYCLE-SEAT.

SPECIFICATION forming part of Letters Patent No. 274,163, dated March 20, 1883.

Application filed September 21, 1882. (No model.)

To all whom it may concern:

Be it known that I, JOSEPH L. WILSON, of Waltham, in the county of Middlesex and State of Massachusetts, have invented a certain new and useful Improvement in Bicycle-Seats, of which the following is a description sufficiently full, clear, and exact to enable any person skilled in the art or science to which said invention appertains to make and use the same, reference being had to the accompanying drawing, forming a part of this specification, in which the figure is a sectional side elevation.

In ordinary bicycles the saddle of the seat is usually mounted on a flat spring which is rigidly attached to the backbone of the machine. This spring, while taking up or neutralizing the vertical movements of the seat produced by passing over a rough road or track, does not take up or neutralize to any great extent the horizontal movements produced by the same cause.

My invention is designed to obviate this objection; and to that end I construct and arrange the parts which constitute the seat in a novel and unique manner, as hereinafter fully set forth and claimed, by which a more desirable and effective device of this character is produced than is now in ordinary use.

The nature and operation of the improvement will be readily understood by all conversant with such matters from the following explanation, its extreme simplicity rendering an elaborate description unnecessary.

In the drawing, A represents the main wheel, B the handles, C the saddle, and D the backbone, of the bicycle. A semi-elliptic spring, m, is rigidly secured to the backbone by the nuts and bolts d, each end of this

are jointed thereto in such a manner as to swing freely in line with the springs. A spring, E, is arranged horizontally above the spring m, and has its ends xx curved downwardly and inwardly under the ends of the spring m, 45 where they are jointed to the lower ends of the links aa, as shown, the saddle C being firmly secured to the upper side of the spring E by the nut and bolt v, or in any other convenient manner.

In the use of my improvement it will be obvious that the jar or vertical movements of the backbone D, produced by the wheel A in passing over a rough road or track, will be taken up or neutralized by the conjoint action 55 of the springs E m, and also that the ill or disagreeable effects of all horizontal movements of the seat produced by the wheel coming in contact with obstructions in its path will be overcome by means of the jointed 60 pendulous links aa, and the peculiar manner of forming and connecting the springs E m, whereby the spring E is enabled to move or swing slightly back and forth on the line of traverse followed by the machine.

Having thus explained my improvement, what I claim is—

The combination of the bicycle-backbone D, the upwardly-curved semi-elliptic spring m, connected thereto, the straight longitudinal 70 spring E, having downwardly-curved ends xx, all formed in one piece, the pendulous links aa, connecting the ends of said springs, and the saddle C, attached to said longitudinal springs, substantially as described.

JOSEPH L. WILSON.
